POWDER SEPARATOR AND DISPENSER

Richard F. Berndt, Racine, Wis., assignor to Virk-type Corporation, a corporation of Virginia

Application April 19, 1947, Serial No. 742,759

4 Claims. (Cl. 209—144)

1

This invention relates to a powder separator and dispenser, and while the same is particularly applicable to the process of raised printing, in which powder is distributed upon a traveling sheet or web of material containing a wet impression, it will be apparent that the same may be variously employed, such as in grading finely divided or pulverized particles according to weight.

The invention has primarily for its object to provide a comparatively simple, fast, and efficient mechanism, for separating the light and heavy particles in pulverized or powdered material.

Incidental to the foregoing, a more specific object of the invention resides in the provision of a centrifugal air separator equipped with a rotary discharge valve for uniform delivery of the heavier separated particles.

A further object in connection with raised printing machines, is to provide suction means communicating with the separator for removing surplus powder from a printed surface for cleaning, grading, and subsequent distribution.

Another object is to provide means for controlling the character of separation, whereby particles of varying predetermined weight may be segregated for distribution.

In addition to the foregoing, other objects will appear as the description proceeds, and while the accompanying drawing illustrates one complete physical form of the invention constructed in accordance with the best mode so far devised, it is to be understood that changes in the precise embodiment of the invention are contemplated within the scope of the appended claims.

In the drawing:

Fig. 1 is an elevational view, partially in section, of a device incorporating principles of the present invention and illustrating the device applied to a raised printing machine;

Fig. 2 is an enlarged fragmentary vertical sectional view taken on the line 2—2 of Fig. 3;

Fig. 3 is a similar view taken on the line 3—3 of Fig. 2; and

Fig. 4 is a schematic illustration of a modified form of the invention.

With particular reference to the accompanying drawing, the numeral 1 designates a support upon which a valve body 2 is mounted for reception of a rotary valve 3. An inclined chute 1' carried by the support 1, delivers the powder to a given point.

Attached to the top of the valve body 2 is a centrifugal separator case 4, in which a reduced

2

pressure is created through a suction line 5 communicating with one side of the casing. A nozzle 6 carried by the separator casing, and communicating with the same tangential to its arcuate periphery, is provided at its lower end with a suction head 7 for collecting surplus powder from a printed and dusted sheet of material, traveling on a belt 8 over a carrier roll 9 in a raised printing machine.

10 The distributing valve 3 comprises a pair of circular end plates 10, the inner faces of which are provided with spaced radial grooves 11 for reception of the ends of a plurality of fins 12. The circular end plates 10 are mounted on a 15 shaft 13, which is grooved longitudinally for reception of the inner edges of the fins 12. The ends of the shaft 13 are journaled in bearings 14 carried by the stand 1, and in that form of the invention illustrated in Figs. 1 to 3, the valve 20 is continuously rotated by a suitable driving connection with a sprocket or pulley 15 secured to one end of the shaft 13.

Obviously, the fins 12 serve to divide the valve 3 into a plurality of annular disposed pockets, 25 which receive powdered material from the centrifugal separator 4 through an orifice 16 formed in the valve body 2, and providing a communication between a depending delivery spout 18, comprising part of the centrifugal separator, and 30 a semi-circular recess 17 in the valve body in which the valve 3 rotates.

It is important that the recess 17 have no underhanging portions upon which powder passing through the valve might be supported, because the characteristics of the powder with 35 which it is contemplated that my apparatus will be used are such that it will tend to build up on such underhanging portions and clog the valve. Therefore the circularly arcuate recess 17 must not subtend an angle of more than 180°.

40 For the purpose to be later described in connection with the operation of the present device, in some instances it is desired to provide a variable circulation of air through the heavier particles 45 prior to their delivery into the pockets of the valve 3. One method by which this may be accomplished is to provide a variable clearance between the outer ends of the radial fins 12 and the annular recess 17 in the valve body 2. The 50 fins 12 are, therefore, slidably mounted in the grooves 11 of the circular end plates 10 and the longitudinal grooves in the shaft 13. For radially shifting the fins, the same are provided on their opposite ends with pins 19 that extend through 55 slots 20, formed in the circular end plates 10 and

into a series of tangential slots 21 formed in a pair of annular rings 22, carried by and rotatably adjustable with relation to the end plates. Set screws 23 serve to lock the rings 22 and fins 12 in adjusted position.

During operation of the machine, pressure within the casing 4 is reduced through the suction line 5, and the valve 3 is rotated by the drive sprocket 15, or by gravity as hereinafter described. An initial supply of powder contained in the chute 1' is then released by raising a gate 1'', and discharged in a fine stream transversely of the traveling belt 8 to either sheets or a web of material previously receiving a wet or printed impression, causing a portion of the powder to adhere to the sheet.

The printed and dusted sheet then travels below the suction head 7 of the nozzle 6, and surplus powder not adhered to the sheet is collected and drawn into the separator casing 4 by the reduced pressure created therein.

Due to the centrifugal air action created within the separator, the heavier particles of powder are discharged through the spout 18 into the pockets of the valve 3, while the lighter particles and floating dust are removed through the suction line 5. Rotation of the valve 3 then causes the collected powder to be delivered to chute 1' for repeated use.

Thus it will be seen that although the surplus powder is repeatedly used, the same is continuously cleaned and graded to provide a uniform supply to the printed material traveling under the chute 1'.

Inasmuch as the present dispenser permits the use of a comparatively large orifice through which material is delivered from the separator to the rotary valve, static is reduced to a minimum, and because of a slight up-draft pass the valve and through the separator, a further separating action occurs to remove the fine particles or dust that might adhere to the heavier particles discharged into the delivery spout 18 through centrifugal action of the separator.

In some instances it may be desired to eliminate the external drive of the rotary valve 3, as shown in the modification illustrated in Fig. 4, in which the center of the valve is offset laterally with relation to the axis of the orifice 16, thus causing over-balance of the valve to affect its rotation.

For the purpose of regulating, grading, and separation of the finely divided particles to a high degree of accuracy, clearance between the fins 12 and the valve body recess 17 is controlled by radial shifting of the fins to vary the up-flow of air around the valve and through the separator. Radial adjustment of the fins 12 is easily accomplished in the structure described by loosening the set screws 23 and rotating the rings 22, in which the tangential slots engage the pins 19 carried by the fins to cause the fins to shift inwardly or outwardly, depending upon the direction of rotation of the rings.

An alternate method of introducing a regulated circulation of air through the separate heavier particles prior to their delivery into the valve pockets, is shown in Fig. 4, in which the valve fins 12' are not adjustable, but closely fitted to the valve recess 17 to provide practically no clearance. Instead an elongated slot 24 provided in the valve body, and controlled by a plug valve 25, forms an air passage to the valve orifice 16.

From the foregoing explanation considered in connection with the accompanying drawing, it

will be apparent that an exceedingly simple and efficient centrifugal air separator and dispenser has been devised for grading and cleaning pulverized or finely divided powdered particles, and when applied to a raised printing machine, a continuous even flow of uniform material is delivered to a traveling printed sheet, from which excess powder is removed and cleaned for subsequent use, thus effecting a material economy in the consumption of powder, and insuring a high quality of raised printing.

When merely used for grading, the powdered material can be delivered directly to the suction head 7 from a hopper or other source of supply, and the collected heavier particles discharged into a suitable receiving container.

I claim:

1. In apparatus of the type described including a centrifugal separator, a valve for controlling the flow of powder from the separator which comprises a valve body having an inlet orifice in its upper side adapted to receive powder from the separator, a recess in the bottom side of the valve block and in communication with said orifice, said bottom side of the valve block lying in a substantially horizontal plane and said recess being circularly arcuate in cross section and subtending an angle of not substantially more than 180°, and a dispensing valve mounted to rotate through said recess, said dispensing valve including spaced radial fins forming a plurality of receiving pockets, and said fins being spaced from the wall of said recess to allow passage of air into said separator through said recess and said inlet orifice.

2. In apparatus of the type described including a centrifugal separator, a valve for controlling the flow of powder from the separator which comprises a valve body having an inlet orifice in its upper side adapted to receive powder from the separator, a dispensing valve rotatably mounted in the valve body on a supporting shaft and including spaced radial fins mounted in longitudinal grooves in the shaft and forming a plurality of receiving pockets, said fins being spaced from the valve body to allow passage of air into the separator through the valve body and having pins at their opposite ends, a pair of relatively rotatable adjusting plates at each of the opposite ends of the dispensing valve, and a set screw for fixing each pair of plates together, the inner plates having radial grooves formed therein into which the ends of the fins extend, the pins extending through radial slots in said inner plates, and the outer plates having non-radial slots for receiving the pins, whereby when the inner and outer plates are rotated relative to one another, the fins are moved radially to adjust the spacing between them and the valve body.

3. In apparatus of the type described including a centrifugal separator, a valve as set forth in claim 2 which includes a recess in the bottom side of the valve block and in communication with said inlet orifice, said recess being adapted to have the dispensing valve rotate through it and being circularly arcuate in cross section and subtending an angle of not more than 180°.

4. In apparatus of the type described including a centrifugal separator, a valve for controlling the flow of powder from the separator which comprises a valve body having an inlet orifice in the upper side adapted to receive powder from the separator, a recess in the bottom side of the valve block and in communication with said orifice, said bottom side of the valve block lying in

75

a substantially horizontal plane and said recess being circularly arcuate in cross section and subtending an angle of not substantially more than 180°, a dispensing valve mounted to rotate through said recess, said dispensing valve including spaced radial fins forming a plurality of receiving pockets, the radially outer edges of said fins being spaced from the wall of said recess to allow passage of air into said separator through said recess and said inlet orifice, and means for radially adjusting said fins to regulate the spacing of said outer fin edges from the recess wall thereby to regulate said passage of air.
